UNITED STATES PATENT OFFICE.

EDWARD F. TIPTON, OF SAN FRANCISCO, CALIFORNIA, ASSIGNOR, BY MESNE ASSIGNMENTS, OF ONE-FOURTH TO CLARENCE H. ADAMS, OF SAN FRANCISCO, CALIFORNIA.

DESIGN FOR A RADIATOR CAP.

Application filed April 23, 1927. Serial No. 21,698. Term of patent 14 years.

To all whom it may concern:

Be it known that I, EDWARD F. TIPTON, a citizen of the United States, residing at 575 Capp Street, city and county of San Francisco, State of California, have invented a new, original, and ornamental Design for Radiator Caps, of which the following is a specification, reference being had to the accompanying drawing, forming part thereof.

Figure 1 is a side elevation of a radiator cap showing my new design, and

Figure 2 is a front view thereof.

I claim:

The ornamental design for a radiator cap as shown.

EDWARD F. TIPTON.
